CLAIM

The ornamental design for a teak chair, as shown and described.

DESCRIPTION

The patent or application file contains at least one drawing executed in color. Copies of this patent or patent application publication with color drawing(s) will be provided by the Office upon request and payment of the necessary fee.

FIG. 1 is a left side perspective view of a teak chair showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a front perspective view thereof;

FIG. 8 is a right side perspective view thereof; and,

FIG. 9 is a rear perspective view thereof.

The broken lines in the drawings illustrate portions of the teak chair that form no part of the claimed design.
